(57) **CLAIM**

I claim the ornamental design for a leader line gripping and wrapping tool, as shown and described.

DESCRIPTION

FIG. 1 is a front, side and top perspective view of the leader line gripping and wrapping tool showing a leader line positioned within the central groove of the tool;

FIG. 2 is a front, side and top perspective view of the leader line gripping and wrapping tool showing the removable wrapping knob removed from the main body of the tool;

FIG. 3 is a front and side perspective view of the leader line gripping and wrapping tool;

FIG. 4 is a rear and side perspective view of the leader line gripping and wrapping tool;

FIG. 5 is top plan view of the leader line gripping and wrapping tool;

FIG. 6 is a bottom plan view of the leader line gripping and wrapping tool;

FIG. 7 is a side elevation view of the leader line gripping and wrapping tool, with the opposite side elevation view being a mirror image;

FIG. 8 is a front view of the leader line gripping and wrapping tool; and,

FIG. 9 is a rear view of the leader line gripping and wrapping tool.

The broken line showing of environment in FIG. 1 is included for the purpose of illustrating only and forms no part of the claimed design.
